BURIAL VAULT

Harold F. Kuettner, Dundee, Ill.

Application August 14, 1935, Serial No. 36,227

5 Claims. (Cl. 72—7)

This invention relates to an improved burial vault of the type used in graves to house a coffin, and one object of the invention is to provide a device of this character which will be very strong 5 and prevent a coffin from collapsing due to the weight of earth above it.

Another object of the invention is to provide the vault with a hood or upper portion consisting of concrete or an equivalent material disposed 10 about a metallic liner which serves to prevent gases reaching the concrete and seeping through the same.

Another object of the invention is to so construct the liner that it will be firmly anchored to 15 the concrete or cement from which the hood is formed and thus prevent any danger of the liner working loose from the concrete.

Another object of the invention is to provide an improved base upon which the hood rests 20 about a platform which directly supports the coffin, the base and hood being so constructed that water will be prevented from moving upwardly into the hood, a sufficient distance to reach the coffin and causing the coffin to rot quickly 25 due to becoming wet by being immersed in water.

Another object of the invention is to provide a coffin-supporting platform which is formed in 30 sections capable of being easily set in place, the platform sections and the base being of such formation that the platform sections will be firmly held against movement longitudinally or transversely of the base when in place thereon.

The invention is illustrated in the accompanying 35 drawings, wherein

Figure 1 is a perspective view of the improved vault with the hood shown in an elevated position above the base.

Figure 2 is a vertical sectional view taken longitudinally through the vault.

Figure 3 is a longitudinal sectional view taken horizontally through the vault along the line 3—3 of Figure 2.

Figure 4 is a perspective view of a portion of 45 the liner.

This improved vault consists, briefly, of a hood 1, a base 2 upon which the hood rests when in place, and a platform consisting of end sections 3 and an intermediate section 4 which rests upon 50 the base between the end sections. The base is set into a grave at the bottom thereof and the platform sections then lowered into the grave and set in place and after the coffin has been lowered and brought to rest upon the ribs 5 and 55 6 of the platform sections, the hood may then be lowered and it rests upon the base about margins of the platform. The coffin will thus be enclosed in concrete which will prevent burrowing animals from having access to the coffin and 60 as air will be confined in the hood, water which

may seep into the vault about margins of the platform sections will cause air confined in the hood to be compressed and the water will be prevented from rising in the hood a sufficient distance to reach the coffin which rests upon the 5 ribs of the platform.

The base is in the form of an oblong frame having side bars 7 and end bars 8 and referring to Figures 1 and 2 it will be seen that outer side faces of these bars are shaped to define downwardly sloping surfaces 9 and shoulders 10 which project from the sloping faces in spaced relation to each other longitudinally thereof and taper upwardly. The upper ends of the shoulders 10 are rounded and flush with the flat upper faces 11 of the side and end bars and, therefore, when the hood is set in place with the flat lower edge faces of its side and end walls 12 and 13 resting upon the flat faces 11 and the rounded upper 15 ends of the shoulders 10, the hood will be firmly supported. The fact that the hood has contacting engagement with the marginal edge faces of the platform sections prevents the hood from shifting longitudinally or transversely of the base, this being due to the fact that the platform sections have thickened portions which extend downwardly between the side and end bars 20 of the base for contacting engagement with inner side faces of these bars and with side faces 30 of cross bars 14 extending between the side bars 35 of the base. These cross bars serve to strengthen the base and are so located that the abutting marginal edge portions of the platform sections rest upon their upper faces, as shown in Figures 2 and 3. The weight of the platform sections and a 40 coffin resting thereon will thus be distributed over the side and end bars and cross bars of the base and there will be no danger of the concrete base cracking or breaking under the weight.

The hood is also formed of concrete and while 45 it is important that it have side and end walls formed integral with a top 15 and thus provide a hood having the configuration of a bell, it will be obvious that any desired external configuration and ornamentation may be provided. Eyes 16 50 are anchored in the side walls of the hood and carry rings 17 through which ropes or the like may be passed and permit lowering of the hood which is heavy without danger of breaking it. In order 55 to reinforce the hood and prevent gases and air from escaping through pores of the concrete, there has been provided a liner 18 formed of copper or any other desired metal. This liner conforms to the internal configuration of the hood 55 and as the liner is placed in a mold and the concrete or cement poured into the mold about the liner when making the hood, the liner and concrete of the hood will have close face to face engagement with each other and the concrete ad- 60

here to the metal liner. Plates 19 having end portions bent to form diverging wings or arms 20 are soldered or otherwise firmly secured to side and end walls of the liner and also upon the 5 upper face of the upper wall of the liner and the wings 20 project from the walls and top of the liner so that they are embedded in the concrete and firmly anchor the liner to the concrete. It should also be noted that lower marginal portions 10 of the side and end walls are bent outwardly and upwardly to form flanges 21 which are embedded in the side and end walls of the hood and reinforce the hood about lower ends of its walls. As portions of the flanges are exposed about inner edges 15 of the lower edge faces of the side and end walls of the hood, these exposed portions of the flanges will make contact with the flat faces 11 of the side and end walls of the base when the hood is lowered into place and there will be less likelihood 20 of the hood being chipped or broken as it is lowered into place. When this vault is in use, the base is set in place in a grave and constitutes a strong and solid foundation for a coffin. The 25 platform sections 3 and 4 are lowered and set in their positions upon the base with the section 4 between the cross bars 14 and the sections 3 between the cross bars and the end bars. It should be noted that the cross bar 6 is formed midway the length of the section 4, whereas the ribs 5 are formed off center and the sections 3 are set 30 in place with the ribs 5 closer to the cross bars 14 than they are to the end bars 2. By this arrangement, the ribs 5 and the rib 6 will be so spaced from each other that when a coffin is lowered in 35 a grave and brought to rest upon the ribs, the rib 6 will be approximately midway the length of the coffin and the ribs 5 spaced equal distances from ends of the coffin and the coffin will be very well supported at three points. After the coffin 40 is in place, the hood is lowered by ropes or the like passed through the rings 17 and brought to rest upon the base with its side and end walls resting upon the side and end walls of the base in close 45 contacting engagement with marginal edges of the platform sections. Any water which may tend to accumulate in the hood during extremely rainy weather will easily drain out during dry weather as side faces of the side and end walls of the base slope downwardly between the shoulders 50 18. Air which is trapped in the hood will prevent water from rising in the hood to a sufficient depth to cause the coffin to be immersed in water and become wet and rot.

Having thus described the invention, what is claimed as new is:

1. A burial vault comprising a base having side and end bars and cross bars extending between the side bars in spaced relation to each other and 60 to the end bars, the side and end bars having downwardly sloping outer faces and shoulders projecting from the sloping faces in spaced relation to each other and having their upper ends flush with the plane of the upper faces of the side 65 and end bars and cross bars, platform sections resting upon upper faces of the side and end bars and cross bars and having portions extending downwardly between the cross bars and side and end bars to contact with inner faces thereof, 70 means projecting upwardly from the platform sections for supporting a coffin in an elevated position, and a hood resting upon upper faces of

the side and end bars and the upper ends of said shoulders, the hood being closed at its top and open at its bottom whereby air may be trapped in the hood when the hood is lowered into place to rest upon the base about the platform sections 5 and prevent water from rising in the hood to a depth to make contact with a coffin.

2. A burial vault comprising a base consisting of a frame having side and end bars and cross bars extending between the side bars in spaced 10 relation to each other, a platform consisting of sections resting upon the cross bars and side and end bars and having depending portions contacting with side faces of the cross bars and side and end bars, ribs projecting upwardly from the 15 platform sections and extending transversely across the same, and a hood closed at its top and having depending side and end walls to rest upon upper faces of the side and end bars of the base with inner faces of the walls of the hood contacting with marginal edge faces of the platform sections.

3. A burial vault comprising a base having side and end bars, a platform carried by said base and having means for supporting a coffin in an elevated 25 position, said platform having portions engaging inner side faces of the side and end bars and having marginal portions resting upon upper faces of the side and end bars and projecting upwardly from the base with its edge faces spaced 30 from outer margins of the upper face of the side and end bars of the base, and a hood formed of set plastic material and having a metal liner fitting snugly about margins of the platform for contact with edge faces thereof when the hood 35 is in place with lower faces of its walls resting upon the projecting portions of the upper faces of the side and end bars of the base.

4. A burial vault comprising a base, a platform carried by said base, a hood of set plastic 40 material disposed over the base and platform and having a closed top and depending walls for resting upon the base about the platform, a metal liner having a top and walls in close contacting engagement with inner faces of the top and walls of the hood and having lower marginal portions of its walls bent outwardly and upwardly and embedded in walls of the hood, and anchoring plates carried by the liner and each having its intermediate portion secured to the liner and its 45 end portions extending outwardly therefrom and embedded in the set plastic material of the hood. 50

5. A burial vault comprising a base consisting of a frame having side and end bars and cross bars extending between the side bars in spaced 55 relation to each other, a platform resting upon the cross bars and side and end bars and having depending portions contacting with side faces of the cross bars and side and end bars to prevent movement of the platform longitudinally and transversely of the base, said platform having its margins spaced from outer side edges of the side and end bars of the base to provide the side and end bars with portions projecting outwardly when the platform is in place, and a hood closed at its 60 top and having depending side and end walls to rest upon the outwardly projecting portions of the upper faces of the side and end bars of the base with inner faces of the walls of the hood contacting with marginal edge faces of the platform. 65
